UNITED STATES PATENT OFFICE.

EMIL B. MEYROWITZ, OF RIDGEFIELD, NEW JERSEY, ASSIGNOR TO THE MEYROWITZ MANUFACTURING COMPANY, OF SAME PLACE.

DESIGN FOR AN EYEGLASS-SPRING.

SPECIFICATION forming part of Design No. 24,418, dated June 25, 1895.

Application filed September 20, 1894. Serial No. 523,648. Term of patent 7 years.

To all whom it may concern:

Be it known that I, EMIL B. MEYROWITZ, a citizen of the United States of America, and a resident of Ridgefield, in the State of New Jersey, have invented and produced a new, useful, and original Design for Eyeglass-Springs, of which the following is a specification, reference being had to the accompanying sheet of drawings.

Figure 1 of the drawings is a front elevation, and Fig. 2 a side elevation, of a reduced tilting spring for eyeglasses, showing my present design. Fig. 3 is a perspective view of the same spring; and Fig. 4 is a perspective view of an unreduced spring embodying the same design, as hereinafter set forth.

The design consists in the new, useful, and original shape or configuration of the spring as represented by the drawings; its principle feature being the forward slant or "tilt" of the upper part or bow, *b*, of the spring in a straight line from the upper ends of a pair of vertical shanks, *s*, as best seen in Fig. 2.

The shanks *s* have parallel front and rear edges, 1 and 2, Fig. 2, and are provided with central holes, 3, Fig. 2; and at their upper ends they merge into the ends of the bow *b* by inner and outer angles, 4 and 5, Fig. 2, at front and rear respectively, which determine said forward tilt of the bow, and by curves, 6, Fig. 1, which merge into the curves of the bow.

In the reduced spring, represented by Figs. 1, 2, and 3, the bow *b* tapers gradually in width from at or about said curves 6 to at or about points 7, Fig. 1, between which the edges of the top of the bow are parallel with each other, and its upper surface is rounded.

In the modified spring represented by Fig. 4 the bow *b* throughout its length is of the same width as the shanks *s*. Otherwise the two springs are alike, and the same light and novel appearance characterizes both.

It will be understood from the above that the particular shape of the bow *b* is not considered a material feature of the present design. 45

It will also be apparent that I do not claim herein broadly a "tilting" spring for eyeglasses whether such spring be "reduced" or 50 not. Such springs broadly considered are set forth in my patents of invention, No. 368,226, dated August 16, 1887, and No. 469,437, dated February 23, 1892. The effect of the present design is not only to tilt the spring out of contact with the forehead but to do this by a 55 novel shape of the spring itself, of a pleasing and attractive appearance, having the easily recognizable characteristic illustrated by Fig. 2 as aforesaid.

The term "reduced" is used in this specification, as in the trade, to signify a modification common to various shapes of eyeglass springs in which the spring tapers from both ends toward the middle so as to render the 65 middle reduced in width and thus to make the spring lighter and less conspicuous than springs not so reduced; and the term "unreduced" is used to describe that modification of such springs in which the finished spring 70 is not so reduced, as illustrated by Fig. 4 of the accompanying drawings.

What I claim as new, and desire to patent under this specification, is—

The new, useful and original shape or configuration of eyeglass springs characterized by a forward tilt of the bow of the spring in a straight line from the upper ends of a pair of vertical shanks, as shown and described. 75

E. B. MEYROWITZ.
